UNITED STATES PATENT OFFICE.

ORVAL R. PLATTER, OF NORTH VERNON, INDIANA.

PORCH-SWING END POCKET.

Application filed April 23, 1924. Serial No. 708,467.

To all whom it may concern:

Be it known that I, ORVAL R. PLATTER, a citizen of the United States, residing at North Vernon, in the county of Jennings 5 and State of Indiana, have invented certain new and useful Improvements in Porch-Swing End Pockets, of which the following is a specification.

This invention relates to improvements 10 in the construction of porch swings and the like.

The primary object of this invention is the provision of a novel pocket arrangement adapted to be used in connection with porch 15 swing structures, so that sewing, books, magazines, and like loose articles may be maintained on the swing in an orderly arrangement.

Other objects and advantages of this invention will be apparent during the course 20 of the following detailed description.

In the accompanying drawing, forming a part of this specification, and wherein similar reference characters designate corresponding parts throughout the several views—

Figure 1 is a perspective view of the improved swing, showing the preferred construction of the same and the association 30 of the swing pockets therewith.

Figure 2 is a cross sectional view taken through the arm structure of the porch swing, showing in plan view the preferred arrangement of the swing pocket, the view 35 being taken on the line 2—2 of Figure 3.

Figure 3 is a cross sectional view taken substantially on the line 3—3 of Figure 2.

In the drawing, wherein for the purpose of illustration is shown only the preferred embodiment of the improved swing, and the end pocket structure therefor, the letter A 40 may generally designate the improved swing, which is adapted to have end pockets B and C supported at each end thereof.

For the purpose of this invention the swing A may consist of a seat portion 10; back portion 11; end sills 12 connected at the ends of the seat portion, and at each end of the seat 10, at the ends of each of 45 the sills 12 vertical or upright posts or standards 13 and 14 are provided for supporting an arm rest 15 thereon in a spaced relation above the sill 12, and preferably parallel therewith. In the space between these posts 50 13 and 14, and the sill 12 and its arm rest, the pockets B or C are adapted to be

placed in a projecting relation outwardly from the end of the swing, so that loose articles may be received in the pockets for support in an orderly arrangement at the ends 60 of the swing.

The swing A is, of course, supported by cables at each end thereof, and the cable at each end of the swing preferably comprises the strands 18 and 19 connected by eye bolts 20 and 21 respectively; the eye bolts 20 and 21 having the hook portions thereof extending upwardly above the arm rests 15 for receiving the lowermost links of the cable strands 18 and 19. These eye bolts 20 and 21 are also used for detachably maintaining the pocket structures B or C in place, as will be subsequently described. The eye bolts 20 and 21 both extend transversely through suitable apertures 24 provided 70 through the arm rest 15, and extend in parallel spaced relation adjacent the end posts 13 and 14, and at their lower ends extend through passageways 26 provided through the end sills 12, and at their lower ends receive nuts 28 whereby they are maintained in place to perform their dual function.

Each of the pocket structures B and C 75 consists of a floor portion 35, which is relatively narrow, and at the ends of which the side walls 36 and 37 are provided, in right angled upwardly extending relation thereto. The walls 36 and 37 are analogous, and the inside edges 39 thereof are at right angles to the plane of the floor 35, whereas the outside edges 40 of the walls 36 and 37 taper upwardly at an angle greater than 90° 80 with respect to the plane of the floor 35, so that the walls 36 and 37 gradually increase 85 in width toward their top marginal edges 35. Inside slats 46 are attached to the inside edges 39 of the walls 36 and 37, as a retaining feature for the articles to be received in the pockets, and slats 48 are attached to the outside edges 40 of the side walls 36 and 37. It is thus apparent that 90 the pocket compartment decreases in width from the top of the structure B or C toward 95 the floor portion 35.

With respect to the assemblage of the pockets B and C in their respective ends of the swing A, it is to be noted that the eye bolts 20 and 21 are to be spaced from their respective adjacent posts 13 and 14, so that 100 the walls 36 and 37 will be received in said spaces when assemblage is effected. The 105

110

floor 35 of the pockets B or C rests upon its adjacent end sill 12, substantially as is illustrated in Figure 3 of the drawing, and in this relation the top edge 45 of the pocket just rests below the lower surface of the arm rest 15. In this position the eye bolts 20 and 21 are placed as above described, and it is to be noted that the walls 36 and 37 are provided with vertical grooves or channels 55 inwardly from their inside surface for receiving the intermediate portion of the eye-bolts, whereby to retain the pocket structure B or C in its respective end of the swing, in a stable relation therewith, so that a portion of the pocket extends laterally of the outer edge 57 of the arm rest 15, at the top thereof, whereby articles may be readily slipped into the pocket. The inside slats or retaining pieces 46 are positioned in a vertical plane; whereas the slats 48 are positioned in a plane at an acute angle to the vertical.

From the foregoing description of this invention it is apparent that an end pocket structure for the ends of swings has been provided, which is simple in construction, and which may be used upon conventional porch swing structures to receive various articles which are ordinarily thrown upon the swing seat, such as sewing, books, magazines, and the like.

Various changes in the shape, size, and arrangement of parts may be made to the form of the improved structure herein illustrated and described, without departing from the spirit of this invention or the scope of the claims.

I claim:

1. In a structure of the class described the combination of a seat portion including an end sill, an arm rest supported above the end sill, bolts extending through the arm rest and into the end sill, and a pocket structure detachably carried by said bolts between the arm rest and end sill so that a portion of the pocket is open laterally of the arm rest at the top thereof.
2. In a porch swing the combination of a seat structure including an end sill, an arm rest supported upwardly of the end sill and in spaced relation with the sill, eye bolts detachably carried by the arm rest and extending through the end sill, and a pocket structure including side walls having grooves therein; said eye bolts adapted to be received in said grooves to hold the pocket

structure on the swing below said arm rest and upon said end sill.

3. In combination with a swing structure including an end sill posts carried at the ends of the end sill, and an arm rest supported by the posts in spaced relation above the end sill, bolts detachably carried by the rest and extending through said end sill, said bolts being placed adjacent said posts in a spaced relation therewith, and a pocket structure including side walls and a floor, said floor adapted to rest upon the end sill and said side walls adapted to be received between said posts and said eye bolts with the eye bolts disposed in lateral grooves which are formed in said side walls of the pockets.

4. In a device of the class described the combination of a seat having an end sill, spaced end posts connected with the seat extending upwardly at the ends of said end sill, an arm rest carried upwardly by the end posts in spaced relation above said end sill, said end posts, sill, and arm rest providing an opening, a pocket structure including side walls with longitudinal ways therealong, said pocket being adapted to be slipped into the opening provided between said end posts with the side walls thereof in abutment with said end posts, and bolts carried at their upper and lower ends by said arm rest and sill and extending through the ways of said side walls for detachably connecting the side walls between said bolts and end posts.

5. In a device of the class described the combination of a seat having an end sill, spaced end posts connected with the seat extending upwardly at the ends of said end sill, an arm rest carried upwardly by the end posts in spaced relation above said end sill, said end posts, sill, and arm rest providing an opening, a pocket structure including side walls with longitudinal ways therealong, said pocket being adapted to be slipped into the opening provided between said end posts with the side walls thereof in abutment with said end posts, bolts carried at their upper and lower ends by said arm rest and sill and extending through the ways of said side walls for detachably connecting the side walls between said bolts and end posts, said bolts above said end sill being provided with eyes, and cable means connected with said eyes of the bolts for supporting the seat as a swing.

ORVAL R. PLATTER.
